DESIGN FOR A VAPOR-STOVE.

No. 39,574.

Specification for Design.

Patented Sept. 22, 1908.

Application filed May 27, 1908. Serial No. 435,340. Term of patent 7 years.

To all whom it may concern:

Be it known that we, GEORGE E. SAVAGE and EDWARD A. GUTERMANN, citizens of the United States, residing at Meriden, county of New Haven, State of Connecticut, have invented a new, original, and ornamental Design for a Vapor-Stove, of which the following is a full, clear, and exact description.

Our invention relates to a new, original and ornamental design for a vapor stove.

In the drawing, we have shown the same in perspective.

The design comprises a vapor stove body of circular outline having depending flanges at its perimeter from which the stove legs extend, said body having a centrally cut-away or open portion at the top within which the

burner is concentrically seated with the burner valve extending radially at one side, a supply tube radially at the opposite side, the supply tube being surmounted by an ornamental bracket carrying a font of ornamental design. The top of the body portion carries a plurality of radially disposed vessel supports and the burner carries a plurality of radially disposed vessel supports.

We claim:

The ornamental design for a vapor stove as shown and described.

GEORGE E. SAVAGE.

EDWARD A. GUTERMANN.
